(57) **CLAIM**

The ornamental design for a bottle, as shown and described.

DESCRIPTION

The nature of this product is a bottle suitable for holding and dispensing cleaning solution.

FIG. 1 is a top, right, front perspective view of a bottle embodying our new design;

FIG. 2 is a front elevational view thereof;

FIG. 3 is a right side elevational view thereof, the left side elevational view being a mirror image of the right side shown;

FIG. 4 is a top plan view thereof;

FIG. 5 is a bottom plan view thereof; and,

FIG. 6 is a rear elevational view thereof.

The broken line representations of a bottle neck and threads in FIGS. 1-3 and 5-6 are for the purpose of illustration only, and form no part of the claimed design.
